UNITED STATES PATENT OFFICE.

CHESTER D. AINSWORTH, OF WOLLASTON, MASSACHUSETTS, ASSIGNOR, BY MESNE ASSIGNMENTS, TO CONDIT ELECTRICAL MANUFACTURING CORPORATION, OF BOSTON, MASSACHUSETTS, A CORPORATION OF MASSACHUSETTS.

ELECTRIC SWITCH.

Application filed December 14, 1921. Serial No. 522,228.

To all whom it may concern:

Be it known that I, CHESTER D. AINSWORTH, a citizen of the United States, residing at Wollaston, in the county of Norfolk and State of Massachusetts, have invented an Improvement in Electric Switches, of which the following is a specification.

This invention relates to electric switches and has particular reference to electrically operated switches adapted to be enclosed removably in cells.

One of the objects of this invention is to provide an electric switch and a self-contained electrical operating device as a switch unit.

A further object is to arrange the switch so that the switch and its terminals are enclosed in the cell and the electrical operating device is disposed externally of the cell.

20 A further object is to provide the switch with means adapted to form a part of the closure for the cell.

For certain purposes, cell or truck type switches are of the single pole type and for 25 the control of multi-phase circuits, there will be an independent switch for each phase of the circuit; and the switches will be installed in independent adjacent cells; and the switches are arranged to be operated 30 simultaneously to control the multi-phase circuit. The switches are also arranged to be removed independently from their enclosing cells for inspection when desired.

A further object of the invention is to provide operating means connecting the 35 switches of a circuit and extended between the switches externally in front of the cells, and so arranged that the connection of the operating means between the switch to be 40 removed and adjacent switches is accomplished without removal of bolts and the like.

A further object is to arrange the connecting means so that the connection between adjacent switches cannot be broken until the switches are in a predetermined condition.

A further object is to provide each switch 50 of a multi-phase circuit with independent electrically-operated operating means and to connect all operating means of the switches for conjoint operation to open and close the switches.

A further object is to provide a cell-type switch with its electrically-operated operating means removable therefrom and with means by which the operating means of other switches of the circuit may operate a switch having no individual electrically-controlled operating means. 55 60

A further object is generally to improve the construction and operation of electric switches.

Certain features of this invention are disclosed in my co-pending applications, Serial 65 No. 585,672, filed September 1, 1922; Serial No. 522,227, filed December 14, 1921; and Serial No. 535,220, filed February 9, 1922.

Fig. 1 is a front view of a series of switches embodying the invention arranged 70 in cells and with the doors of the center cell removed.

Fig. 2 is a plan view of Fig. 1, with the cell walls illustrated in section and with the center switch partially withdrawn from its 75 cell.

Fig. 3 is a side view of a switch of Figs. 1 and 2.

Fig. 4 is a front view of the operating shaft of the closing magnet and illustrating 80 more particularly the connections between the shafts of adjacent switches.

Fig. 5 is a side detail illustrating the positions of the switch operating and locking arms of the closing magnet shaft in switch- 85 closed and switch-open positions.

Fig. 6 is an enlarged detail of the connection between the closing magnet lever and the operating shaft.

Fig. 7 is a detail, in side elevation, illustrating the relative position of the complementary parts of the operating shaft coupling in partially separated position.

Fig. 8 is a plan view of Fig. 7.

Fig. 9 is a view of the floating member of 95 the coupling and illustrating more particularly the relative position of the guide ways in its opposite faces.

Fig. 10 is a detail illustrating a modified form of coupling connected to angularly- 100 disposed shafts.

I have herein illustrated my invention applied to three switches adapted for the control of a three phase circuit; and each switch is contained removably in one of the cells 105 A, B and C which are arranged side by side.

Said switches are identical and but one will be described.

The switch comprises the oil receptacle 10 and the switch frame 11, comprising a cover 5 for the receptacle secured, preferably removably, to the top of the receptacle. Stationary switch-members 12 are carried by said frame and depend into the receptacle; and switch-operating mechanism is enclosed 10 by the casing formed by said cover and receptacle. Said operating mechanism is provided with an operating member, as the shaft 13, which is journalled in and projects beyond a side wall of said switch frame. An 15 arm 14 is secured to said shaft, and said arm is adapted to be actuated by the electrically-controlled operating mechanism to open and close the switch.

Said receptacle 10 rests upon and is secured 20 to a truck or carriage 15 having the peripherally-grooved wheels 16 journalled therein. Said wheels are received on a track 17 disposed on and secured to the bottom wall of the cell; and said track serves to 25 locate the switch laterally in the cell. An adjustable stop-member 18 rises from the cell floor to engage and limit the movement of the switch toward the rear of the cell, and a screw 19 carried by the carriage 15 and removably threaded in a fixed member 20 serves to draw the switch against said stop-member and removably lock the switch in the cell.

The tracks of the several cells are arranged 35 in parallel and the stop-members are so adjusted that the switches occupy corresponding positions in the cells.

The electrically-controlled operating mechanism for the switch mechanism includes 40 the closing coil comprising the iron-clad solenoid 25 carried by the bracket 26 which forms a cover-plate for one end of the solenoid; and a plate 27 forms a cover for the other end of the solenoid.

Said closing coil is attached removably to 45 the switch frame by suitable means, as the bolts 28. For certain purposes, it may be secured directly to the switch frame (not shown) and for other purposes, and as here shown, an adapter block 29 may be interposed 50 between the switch frame and the closing coil for the purpose of extending the closing coil sufficiently beyond the switch to enable the switch to be enclosed in the cell and the closing coil, and other switch-operating mechanism, associated with said coil, to extend beyond the cell.

A plate 30 is carried by said adapter block 29, and said plate extends vertically 60 above and below the electrically-controlled switch-operating mechanism, and laterally beyond the switch casing to engage the side walls of the cell and form a partial closure for the front of the cell. A plate 31 may be hinged removably, as by the ears 32

formed in the upper edge of said plate, to the upper portion of the cell walls and depend over the side walls of the cell and the upper edge of said plate 30 to cover and enclose the upper portion of said cell. 70 A similar plate 33, having ears 34 received removably in slot 35 in said plate 30, may depend from said plate 30 to cover the lower portion of said cell. The lower portion of said plate 32 may be formed with slots 36 75 therein in which the tracks 17 may be received.

It will be noted that if an explosion accompanied with fire takes place within the cell, the hinged plate 31 and 33, comprising 80 cell doors, will swing outwardly to relieve the pressure within the cell and will thereafter close to enclose the fire within the cell.

The cover plate 27 of the solenoid 25 is formed with an ear 38 and a pair of links 39 are pivoted to opposite sides of said ear and depend therebelow. A pin 40 connects the lower end of said links and a cam roller 41 is rotatably disposed thereon between said links. A plunger or core 42 is movably extended in said solenoid and the end thereof is pivotally secured to said links by the pin 43.

A remote control switch, to which this invention relates, is usually provided with an auxiliary switch for signalling and other purposes. For a multi-phase switching unit herein illustrated, but one auxiliary switch need be employed, as all switches of the unit are arranged to be operated in unison. The auxiliary switch 45 is here shown as carried by and on top of the closing coil 25 of the middle switch, as illustrated in Fig. 1. A movable member 46 of said auxiliary switch is pivotally connected to the end of a lever 47 and said lever is pivotally mounted between the lugs 48 extended from the cover plate 27 at the side-portion thereof. The lower end of said lever is pivotally and loosely-connected to the pin 43 of the closing coil links. It will be obvious that as said closing coil is energized to close the switch and said links move inward, the auxiliary switch will be operated to assume one condition, and when said links move outward, on the opening movement of the switch, said auxiliary switch will be operated to assume another condition. While the closing coil is adapted to be but momentarily energized to close the switch, means hereinafter to be described, are provided to hold the links 39 in a switch-closed position until the switch is opened.

Said bracket 26 is provided with a housing 50 for an overload or trip coil disposed below the closing coil; and the movable member 51 of said trip coil depends below said housing.

An operating shaft 55 is rotatably supported in suitable bearing members 56 car-

ried by said housing 51 and disposed below said closing coil. An arm 57 is fixed to said shaft between said bearing members and its upper end is formed with a cam face adapted 5 to be engaged by the cam roller 41 of the movable members of the closing coil to rock said shaft and close the switch. Links 58 loosely connect with the links 39 of the closing coil with the upper end of said arm 57 10 to cause the auxiliary switch 45 to correspond with the condition of the main switch and also to prevent said links 39 from being thrown upwardly out of operative relation with said arm 57 when the switch is opened. 15 Said arm 57 extends downwardly below the operating shaft 55 and a latch lever 59 is pivoted thereto. Said lever has a notch which engages the fixed pin 60 to hold the switch in closed position, and the movable 20 member 51 of the trip coil 50 is adapted to engage the end of said lever to raise it from engagement with said pin to trip the switch.

An arm 61 is secured to an end of the 25 operating shaft 55 beyond a bearing member 56 and is extended upwardly thereabove and an operating-rod 62 is pivotally connected therewith and extends through an aperture 63 in said plate 30 and is pivotally connected with the arm 14 of the operating shaft 13 of the switch. A spring 65 may be secured to said arm 14 to assist the switch mechanism in opening the switch.

It is obvious that a rotary movement of 35 said operating shaft 55 in a counter-clockwise direction, Fig. 3, will close the switch, and said spring 65 will rotate said shaft in the reverse direction to open the switch.

One of the principal features of the invention 40 is the means for connecting the operating shafts of a series of switches for conjoint operation.

The connecting means, or coupling, is 45 illustrated more particularly in Fig. 1, and Fig. 4 through 10. The coupling comprises the two discs 70 and 70^a each having the hubs 71 and 71^a adapted for attachment to the proximate ends of operating shafts and are secured thereon by the set screws 72. 50 Said discs are formed with the radially arranged dove-tailed splines 73 and 73^a on their end faces. A floating or coupling disc 74 is adapted to connect said discs 70 and 70^a; and said disc 74 is formed with two 55 dove-tailed grooves 75 and 75^a in its opposite end faces arranged at right-angles with each other and shaped to receive slidably the splines 73 and 73^a. Said splined discs 70 and 70^a are assembled with the splines 60 thereof in the grooves in the coupling disc.

The arrangement is such that the shafts to which the discs 70 and 70^a are secured may be relatively eccentric and yet both shafts will be constrained for conjoint rotation at 65 equal angular speeds, the eccentricity of the

shafts being compensated for by sliding movements of the splines in the grooves in the coupling disc, as will be obvious.

By the use of dove-tailed splines, the shafts secured to said discs 70 and 70^a are 70 constrained from relative axial movement and all switches of the gang are tied together. For some purposes it may be desirable to form the coupling with splines having no locking portions, and corresponding 75 grooves, in the coupling disc, and Fig. 10 illustrates such a coupling; and the same results may be accomplished.

The operating shaft 55 of the middle switch of the gang is extended beyond the 80 bearing-members 56 in both directions and discs 70 of the couplings are secured thereto. The operating shafts of the end switches may be extended toward the middle switch, and in line therewith, and the discs 70^a of 85 the couplings are secured thereto. With this arrangement the operating shafts of all switches are secured together for conjoint rotation, and all closing coils may operate 90 collectively to close the switches, or one alone may operate to close the switches; and a single tripping coil and associated mechanism may serve to lock all switches closed, and trip all switches open.

Inasmuch as it may be difficult to align 95 the operating shafts of the switches of the gang accurately in a common or one axis of rotation, this arrangement is particularly desirable as all shafts are rotatably connected and yet each is free to rotate about 100 its own axis.

The form of coupling herein illustrated provides means by which any switch of the gang may readily be disconnected mechanically from the remaining switches. In the 105 switch-open position of the coupling, one of the grooves, as 75^a, in the coupling disc 74, and the corresponding spline, as the spline 73^a, in the disc 70^a, are arranged to be angularly-inclined to the horizontal as 110 indicated in Fig. 5, to prevent the switch from rolling out of the cell when the lock on the switch is removed. However, when the operating shaft is rotated sufficiently in a switch-closing direction to bring the spline 115 and groove into a horizontal plane, or into a plane parallel to the tracks 17 on which the switch is supported, the switch may be moved outwardly from the cell and the coupling will automatically become disconnected. 120

For the purpose of rotating the operating shaft, a socket-member 80 may be secured to the operating shaft, and preferably to the operating shaft of the middle switch of the gang. Said member may be provided with a recess or socket 81 adapted to receive a handle 82 by which the shaft may be rotated. The switches of the gang may also be opened and closed manually with said handle. 125 130

4
It is obvious that the invention may be embodied in other modifications without departing from the spirit thereof.

I claim:

- 5 1. The combination, as a unit, of an oil immersed electric switch having a casing enclosing the switch-members, and electrically-controlled switch-operating means carried by said casing, said operating means including electrical means to move the switch into closed position, mechanism to lock the switch in closed position and permit the electrical means to be de-energized, and electrical means to release the lock on the switch and permit the switch to open.
- 10 2. The combination, as a unit, of an oil immersed electric switch having a casing enclosing the switch-members, wheels by which the casing is movably supported and electrically-controlled switch-operating means mounted externally on said casing, said operating means including electrical means to move the switch into closed position, mechanism to lock the switch in closed position and permit the electrical means to be de-energized, and electrical means to release the lock on the switch and permit the switch to open.
- 15 3. The combination, as a unit, of an oil immersed electric switch having a casing enclosing the switch members and means on which the switch is supported for movement, and electrically-controlled switch-operating means carried by said casing, said operating means including electrical means to move the switch into closed position, mechanism to lock the switch in closed position and permit the electrical means to be de-energized, and electrical means to release the lock on the switch and permit the switch to open.
- 20 4. An oil immersed electric switch having the combination of a casing enclosing the switch-members comprising an oil receptacle and a switch frame comprising a cover for the oil receptacle, and electrically-controlled switch-operating means carried by said switch frame, said operating means including electrical means to move the switch into closed position, mechanism to lock the switch in closed position and permit the electrical means to be de-energized, and electrical means to release the lock on the switch and permit the switch to open.
- 25 5. An oil immersed electric switch having the combination of a casing enclosing the switch-members comprising an oil receptacle, and a switch frame comprising a cover for the oil receptacle, and electrically-controlled switch-operating means mounted externally on said switch frame, said operating means including electrical means to move the switch into closed position, mechanism to lock the switch in closed position and permit the electrical means to be de-energized, and electrical means to release the lock on the switch in closed position.

and permit the electrical means to be de-energized, and electrical means to release the lock on the switch and permit the switch to open.

6. An oil immersed electric switch having the combination of a casing comprising an oil receptacle, a switch frame comprising a cover for said oil receptacle, switch-members and operating mechanism disposed in said casing, said operating mechanism having an operating member extended externally of said casing, and electrically-controlled switch-operating means mounted externally on said switch frame having a member disposed externally of said casing and connected with said operating member, said switch-operating means also having electrical means to lock its member in a position corresponding to the closed condition of the switch, mechanism to lock said member in such position whereby to permit the de-energization of said electrical means, and electrical means to release the lock on said member and cause the switch to open.

7. An electric switch having a casing comprising an oil receptacle, and a switch frame comprising a cover for said oil receptacle, operating mechanism disposed within said casing, and electrically-controlled switch-operating means removably secured externally to said switch frame, said operating means including electrical means to move the switch into closed position, mechanism to lock the switch in closed position and permit the electrical means to be de-energized, and electrical means to release the lock on the switch and permit the switch to open.

8. An electric switch having a casing comprising an oil receptacle, and a switch frame comprising a cover for said oil receptacle, operating mechanism disposed within said casing, said switch frame having a vertically-disposed flange, and an electrically-operated switch-closing coil secured removably to said flange.

9. An electric switch having a casing comprising an oil receptacle, and a switch frame comprising a cover for said oil receptacle, operating mechanism disposed within said casing having a member extended externally beyond the opposite side walls of said casing, and electrically-controlled switch-operating means carried externally by said switch frame having means for operative connection with said operating member on one or both sides of said casing.

10. A portable cell-type electric switch comprising a front cover for the cell, switch operating mechanism disposed on one side of said cover, a switch casing disposed on the other side of said cover, and both mechanism and cover carried by said casing.

11. The combination, with a cell having a front closure therefor, of an electric switch having a casing for the switch members dis-

- posed within the cell behind and supporting said front closure, and electrically-controlled switch-operating means carried by said casing and disposed externally of the cell in front of said front closure.
12. A cell-type electric switch having a casing comprising an oil receptacle and a switch frame comprising a cover for the oil receptacle, and a cell-closing plate carried by said switch frame.
13. A cell-type electric switch having a casing for the switch members, electrically-controlled switch-operating means carried externally by said casing, and a cell-closure carried by said casing and disposed between said casing and said switch-operating means.
14. A cell-type electric switch having a casing comprising an oil receptacle and a switch frame comprising a cover for the oil receptacle, a cell-closing plate carried removably by said switch frame at one end, and electrically-controlled switch-operating means carried by said switch frame beyond said cell-closing plate.
15. A cell-type electric switch having a casing for the switch members, a cell-closing plate carried by the upper portion of said casing, and a cell cover carried by said plate.
16. A cell-type electric switch having a casing for the switch members, a cell-closing plate carried by the upper portion of said casing, and a cell cover secured pivotally to said plate and depending therebelow.
17. A cell-type electric switch having a casing for the switch members, a cell-closing plate carried by the upper portion of said casing, and a cell cover removably secured pivotally to said plate and depending therebelow.
18. The combination of a cell having an entrance, and an electric switch arranged to be moved into the cell and also out of the cell and free from the cell-structure, said switch having a casing and means carried by said casing arranged partially to close the cell entrance when the switch is in the cell, and electrically-controlled switch-operating means carried by said casing beyond said cell closing means.
19. A cell-type electric switch having means whereby it may be moved into the cell and also out of the cell and free from the cell structure, a casing, switch-members and operating mechanism contained within said casing, said operating mechanism having an operating member extended externally of the casing, a cell-closing plate carried by said casing, and electrically-controlled switch-operating means carried by said casing beyond said cell-closing plate having a member extended through an aperture in said plate and connected operatively with the extended member of said switch-operating mechanism.
20. The combination of a cell having an entrance and an electric switch received in said cell, said switch having a plate arranged partially to close the cell entrance, and a cover plate carried by and extended downwardly from the top of the cell at the cell entrance and over the cell cover plate of said switch.
21. The combination of a cell having an entrance, an electric switch received in the cell having a cover plate arranged partially to cover said entrance, a cell door secured to and depending from said cover plate to cover the lower portion of the cell entrance and a second cell door arranged to cover the upper part of the cell entrance.
22. The combination of a cell having an entrance, an electric switch received in the cell having a cover plate arranged partially to cover said entrance, a cell door secured to and depending from said cover plate to cover the lower portion of the cell entrance, a second cell door arranged to cover the upper part of the cell entrance and electrically-controlled switch-operating means carried by said switch externally beyond said cover plate and cell doors.
23. The combination of a plurality of electric switches, each switch having an operating shaft, said switches adapted to be arranged with their respective shafts in approximate co-axial alignment, and means to connect the proximate ends of said operating shafts for conjoint operation in an eccentric alignment of said shafts.
24. The combination of a plurality of electric switches, each switch having an operating shaft, said switches adapted to be arranged with their respective shafts in approximate co-axial alignment, and means to connect the proximate ends of said operating shafts for conjoint operation admitting of the rotary movement of each shaft about its own axis.
25. The combination of a plurality of electric switches each switch having an operating shaft, said switches adapted to be arranged with their respective shafts in approximate co-axial alignment, and couplings connecting the proximate ends of said shafts for conjoint rotary movement, said couplings including interlocked coupling members arranged for separation by a relative movement of said members transverse the line of operating shafts.
26. The combination of a plurality of electric switches, each switch having an operating shaft, said switches adapted to be arranged with their respective shafts in approximate co-axial alignment, and means connecting the proximate ends of said shafts for conjoint rotary movement admitting of the disconnection of said connecting means and the removal of a switch and its operating shaft from the line by a movement of

the switch transverse the line of operating shafts.

27. The combination of a plurality of electric switches, each switch having an operating shaft, said switches adapted to be arranged with their respective shafts in approximate co-axial alignment, and couplings connecting the proximate ends of said operating shafts for conjoint rotary movement, 10 said couplings including interlocked coupling members arranged for separation by a relative movement of said members transverse the line of operating shafts and arranged to be held in connected relation 15 against separation in positions corresponding to switch-closed and switch-open positions.

28. The combination of a pair of electric switches having supporting wheels and operating shafts arranged approximately in axial line and means connecting said shafts for conjoint rotary movement comprising coupling members fixed to the proximate ends of said shafts, each coupling member 25 having radial splines in the end faces thereof arranged at right angles to each other, and a disc having radial grooves in its opposite end faces arranged at right angles to each other disposed between said coupling members 30 with the splines of said coupling members received movably in the grooves in said disc.

29. The combination of a pair of electric switches having supporting wheels and operating shafts arranged approximately in axial lines and means connecting said shafts for conjoint rotary movement comprising coupling members fixed to the proximate ends of said shafts, each coupling member 40 having radial splines in the end faces thereof arranged at right angles to each other, and a disc having radial grooves in its opposite end faces arranged at right angles to each other disposed between said coupling members 45 with the splines of said coupling members received movably in the grooves in said disc, said splines disposed in other than a horizontal position in open and closed conditions of the switch.

30. The combination of a plurality of electric switches, wheeled supporting structures for each switch, whereby the switch may be moved about, individual electrically-controlled switch-operating means carried 55 by each switch, and means connecting the switch-operating means of said switches for the conjoint operation of said switches.

31. The combination of a plurality of electric switches, wheeled supporting structures for each switch, whereby the switch 60 may be moved about, electrically-controlled switch-operating means for at least one of said switches carried by the switch, and means detachably connecting said switch-operating means with all of said switches 65 for the conjoint operation thereof.

32. The combination of a plurality of electric switches, individual operating shafts carried by said switches, and arranged in approximate axial line, means connecting 70 the proximate ends of said operating shafts for conjoint rotary movement, electrically-controlled switch-operating means associated with said operating shafts, and means arranged for the manual rotary movement 75 of all of said shafts associated with one of said shafts.

33. The combination of a pair of electric switches having operating shafts, said switches each having a wheeled supporting 80 structure by which the switch may be moved about, and means connecting said shafts for conjoint rotation including complementary interlocking members carried by said shafts.

34. An electrically-operated electric switch comprising the combination of a closed receptacle, stationary and movable switch members enclosed therein, and an operating coil carried externally by said receptacle having an armature, means operably connecting said armature and movable switch-member, and wheels carried by said receptacle upon which said switch is movable as a unit.

35. A portable electrically-operated electric switch having an enclosing casing including an oil receptacle and a switch frame which forms a cover for said oil receptacle, means connecting said receptacle and casing, stationary and movable switch-members carried by said frame and disposed within the casing, switch-operating mechanism also carried by said frame and disposed within said casing, electrically-operated, switch-actuating means disposed externally of and supported by said frame having means connecting it with said enclosed switch-operating mechanism, and wheels on which said casing is mounted and by which the switch may be moved about.

In testimony whereof, I have signed my name to this specification.

CHESTER D. AINSWORTH.
